(57) **ABSTRACT**

An inductor includes a first magnetic body having a toroidal shape and having a ferrite; and a second magnetic body configured to be different from the first magnetic body and including a metal ribbon, wherein the second magnetic body includes an outer magnetic body disposed on an outer circumferential surface of the first magnetic body and an inner magnetic body disposed on an inner circumferential surface of the first magnetic body, and each of the outer magnetic body and inner magnetic body is wound in a plurality of layers in a circumferential direction of the first magnetic body.

INDUCTOR AND EMI FILTER INCLUDING THE SAME

CROSS-REFERENCE TO RELATED APPLICATIONS

This application is a Continuation Application of U.S. patent application Ser. No. 17/673,245 filed Feb. 16, 2022, which is Continuation Application of U.S. National Stage patent application Ser. No. 16/473,863 (now U.S. Pat. No. 11,289,252), which is a U.S. National Stage Application under 35 U.S.C. § 371 of PCT Application No. PCT/KR2018/000041, filed Jan. 2, 2018, which claims priority to Korean Patent Application No's. 10-2017-0000745, filed Jan. 3, 2017 and 10-2017-0113223, filed Sep. 5, 2017, whose entire disclosures are hereby incorporated by reference.

BACKGROUND

1. Field

Embodiments relate to an inductor and an EMI filter including the same.

2. Background

An inductor is one of electronic components that are used in printed circuit boards, and may be applied to resonance circuits, filter circuits, power circuits, etc. due to the electromagnetic characteristics thereof.

Recently, various electronic devices such as communication devices or display devices have been developed to become smaller and thinner, and according to this trend, an inductor used in these electronic devices is required to be smaller, thinner and highly efficient.

An electromagnetic interference (EMI) filter used in a power board serves to transmit a signal necessary for the operation of a circuit and to remove noise.

FIG. 1 is a block diagram showing a construction in which a general power board equipped with an EMI filter is connected to a power source and a load.

Noise transmitted from the power board of the EMI filter shown in FIG. 1 may be largely classified into radiative noise of 30 MHz to 1 GHz radiated from the power board and conductive noise of 150 kHz to 30 MHz conducted via a power line.

A conductive noise transmission mode may include a differential mode and a common mode. Among these modes, common-mode noise travels and returns along a large loop. Thus, the common-mode noise may affect electronic devices that are located far away even when the amount thereof is small. Such common-mode noise is generated by impedance imbalance of a wiring system and becomes remarkable at a high frequency.

In order to remove common-mode noise, an inductor that is applied to the EMI filter shown in FIG. 1 generally uses a toroidal-shaped magnetic core that includes a Mn—Zn-based ferrite material. Since Mn—Zn-based ferrite has a high magnetic permeability within a range from 100 kHz to 1 MHz, it is capable of effectively removing common-mode noise.

As the power of the power board, to which the EMI filter is applied, is higher, a magnetic core having a higher inductance is required. To this end, a magnetic core having a high magnetic permeability μ , e.g. a magnetic core having relative permeability μ of 10,000 H/m to 15,000 H/m or

higher, is required. However, Mn—Zn-based ferrite having such a high magnetic permeability is expensive. Further, because Mn—Zn-based ferrite has a low core loss ratio due to the material property thereof, the noise removal efficiency within a band of 6 MHz to 30 MHz is low.

BRIEF DESCRIPTION OF THE DRAWINGS

The embodiments will be described in detail with reference to the following drawings in which like reference numerals refer to like elements wherein:

FIG. 1 is a block diagram showing a construction in which a general power board equipped with an EMI filter is connected to a power source and a load.

FIG. 21 shows the noise reduction effect in a differential mode of the comparative example and Embodiment 3 shown in FIG. 18.

FIG. 22 shows the noise reduction effect in a common mode of the comparative example and Embodiment 3 shown in FIG. 18.

FIG. 23 is a view showing the magnetic-field characteristics of a general inductor in a differential mode.

FIG. 24 shows the configuration of the inductor shown in FIG. 23, in which the inductor is divided into three sections.

FIGS. 25A, 25B and 25C show the magnetic permeability of first, second and third sections, respectively, at a certain time point in a differential mode of the inductor according to the comparative example.

FIG. 26 is a graph showing an average magnetic permeability on the y-z plane in a differential mode of the inductor according to the comparative example.

FIG. 27 is a graph showing an average magnetic permeability in a differential mode of the inductor according to the comparative example.

FIG. 28 is a view showing the magnetic-field characteristics of a general inductor in a common mode.

FIGS. 29A, 29B and 29C show the magnetic permeability of first, second and third sections, respectively, at a certain time point in a common mode of the inductor according to the comparative example.

FIG. 30 is a graph showing an average magnetic permeability on the y-z plane in a common mode of the inductor according to the comparative example.

FIG. 31 is a graph showing an average magnetic permeability in a common mode of the inductor according to the comparative example.

FIGS. 32A, 32B and 32C show the magnetic permeability of first, second and third sections, respectively, at a certain time point in a differential mode of Embodiment 3 of the inductor.

FIG. 33 is a graph showing an average magnetic permeability on the y-z plane in a differential mode of Embodiment 3 of the inductor.

FIG. 34 is a graph showing an average magnetic permeability in a differential mode of Embodiment 3 of the inductor.

FIGS. 35A, 35B and 35C show the magnetic permeability (or relative permeability) of first, second and third sections, respectively, at a certain time point in a common mode of Embodiment 3 of the inductor.

FIG. 36 is a graph showing an average magnetic permeability on the y-z plane in a common mode of Embodiment 3 of the inductor.

FIG. 37 is a graph showing an average magnetic permeability in a common mode of Embodiment 3 of the inductor.

FIG. 38 is an embodiment of an EMI filter including an inductor according to an embodiment.

DETAILED DESCRIPTION

Embodiments provide an inductor, which is capable of receiving high power and which is compact and has excellent noise removal performance and a constant inductance, and an EMI filter including the same.

An inductor according to an embodiment includes a first magnetic body having a toroidal shape, the first magnetic body including ferrite, and a second magnetic body configured to be different from the first magnetic body, the second magnetic body including a metal ribbon, wherein the second magnetic body includes an outer magnetic body disposed on the outer circumferential surface of the first magnetic body and an inner magnetic body disposed on the inner circumferential surface of the first magnetic body, and each of the

outer magnetic body and the inner magnetic body is wound in multiple layers in a circumferential direction of the first magnetic body.

For example, the metal ribbon included in the outer magnetic body and the inner magnetic body may be a Fe-based nanocrystalline metal ribbon.

For example, the thickness of the first magnetic body may be greater than the thickness of each of the outer magnetic body and the inner magnetic body in a diameter direction of the first magnetic body.

For example, a thickness ratio between the inner magnetic body and the first magnetic body in the diameter direction may range from 1:80 to 1:16, and a thickness ratio between the outer magnetic body and the first magnetic body in the diameter direction may range from 1:80 to 1:16.

For example, the magnetic permeability of each of the outer magnetic body and the inner magnetic body may be different from the magnetic permeability of the first magnetic body, the thickness of each of the outer magnetic body and the inner magnetic body may be less than the thickness of the first magnetic body in the diameter direction of the first magnetic body, and the saturation magnetic flux density of each of the outer magnetic body and the inner magnetic body may be greater than the saturation magnetic flux density of the first magnetic body.

For example, the thickness of the outer magnetic body and the thickness of the inner magnetic body may be the same as each other in the diameter direction.

An EMI filter according to another embodiment includes an inductor and a capacitor, wherein the inductor includes a first magnetic body having a toroidal shape, the first magnetic body including ferrite, a second magnetic body configured to be different from the first magnetic body, the second magnetic body including a metal ribbon, the second magnetic body including an outer magnetic body disposed on the outer circumferential surface of the first magnetic body and an inner magnetic body disposed on the inner circumferential surface of the first magnetic body, and coils wound around the first magnetic body, the outer magnetic body and the inner magnetic body, and each of the outer magnetic body and the inner magnetic body is wound in multiple layers in a circumferential direction of the first magnetic body.

For example, a thickness ratio between the inner magnetic body and the first magnetic body in a diameter direction of the first magnetic body may range from 1:80 to 1:16, and a thickness ratio between the outer magnetic body and the first magnetic body in the diameter direction may range from 1:80 to 1:16.

For example, the thickness of each of the inner magnetic body and the outer magnetic body in the diameter direction may range from 190 μm to 210 μm .

An inductor according to embodiments and an EMI filter including the same have excellent noise removal performance over a wide frequency band, a reduced size, a large power receiving capacity, and improved performance of removing conductive noise including common-mode noise and differential-mode noise, and is capable of adjusting the noise removal performance for each frequency band.

Exemplary embodiments can be variously changed and embodied in various forms, in which illustrative embodiments are shown. However, exemplary embodiments should not be construed as being limited to the embodiments set forth herein and any changes, equivalents or alternatives which are within the spirit and scope of the embodiments should be understood as falling within the scope of the embodiments.

It will be understood that although the terms "first", "second", etc. may be used herein to describe various elements, these elements should not be limited by these terms. These terms are only used to distinguish one element from another element. For example, a first element may be termed a second element and a second element may be termed a first element without departing from the teachings of the embodiments. The term "and/or" includes any and all combinations of one or more of the associated listed items.

It will be understood that when an element is referred to as being "connected to" or "coupled to" another element, it may be directly connected or coupled to the other element or intervening elements may be present. In contrast, when an element is referred to as being "directly connected to" or "directly coupled to" another element or layer, there are no intervening elements present.

In the description of the embodiments, it will be understood that when an element, such as a layer (film), a region, a pattern or a structure, is referred to as being "on" or "under" another element, such as a substrate, a layer (film), a region, a pad or a pattern, the term "on" or "under" means that the element is "directly" on or under another element or is "indirectly" formed such that an intervening element may also be present. It will also be understood that criteria of on or under is on the basis of the drawing. The thickness or size of a layer (film), a region, a pattern, or a structure shown in the drawings may be exaggerated, omitted or schematically drawn for the convenience and clarity of explanation, and may not utterly reflect the actual size.

The terms used in the present specification are used for explaining a specific exemplary embodiment, not limiting the present inventive concept. Thus, the singular expressions in the present specification include the plural expressions unless clearly specified otherwise in context. In the specification, the terms "comprising" or "including" shall be understood to designate the presence of particular features, numbers, steps, operations, elements, parts, or combinations thereof but not to preclude the presence or addition of one or more other features, numbers, steps, operations, elements, parts, or combinations thereof.

Unless otherwise defined, all terms including technical and scientific terms used herein have the same meaning as commonly understood by one of ordinary skill in the art to which this inventive concept pertains. It will be further understood that terms, such as those defined in commonly used dictionaries, should be interpreted as having a meaning that is consistent with their meaning in the context of the relevant art and will not be interpreted in an idealized or overly formal sense unless expressly so defined herein.

Hereinafter, embodiments will be described in detail with reference to the accompanying drawings. The same elements are denoted by the same reference numerals in the drawings, and a repeated explanation thereof will not be given. Embodiments will be described using a Cartesian coordinate system. However, other different coordinate systems may be used. In the drawings, an x-axis, a y-axis, and a z-axis of the Cartesian coordinate system are perpendicular to each other. However, the disclosure is not limited thereto. The x-axis, the y-axis, and the z-axis may intersect each other.

FIG. 2 is a perspective view of an inductor 100 according to an embodiment.

Referring to FIG. 2, the inductor 100 may include a magnetic core 110 and a coil 120 wound around the magnetic core 110.

The magnetic core 110 may have a toroidal shape, and the coil 120 may include a first coil 122 wound around the

magnetic core 110 and a second coil 124 wound so as to be opposite the first coil 122. Each of the first coil 122 and the second coil 124 may be wound around a top surface TS, a bottom surface BS and a side surface OS of the toroidal-shaped magnetic core 110.

A bobbin (not illustrated) for insulating the magnetic core 110 and the coil 120 may be further provided between the magnetic core 110 and the coil 120.

The coil 120 may be configured as a conductive wire 10 coated on the surface thereof with an insulating material. The conductive wire coated on the surface thereof with an insulating material may include copper, silver, aluminum, gold, nickel, tin, or the like, and may have a circular-shaped or polygonal-shaped cross-section. However, the disclosure is not limited to any particular material of the conductive wire or to any particular shape of the cross-section of the conductive wire.

In the embodiment, the magnetic core 110 may include first and second magnetic bodies. The first and second magnetic bodies are mutually different, and the second magnetic body may be disposed on at least a portion of the surface of the first magnetic body. The magnetic core 110 may be embodied in various forms depending on the configuration in which the second magnetic body is disposed on 20 the surface of the first magnetic body. That is, the second magnetic body may be disposed on at least a portion of the top surface, the bottom surface or the side surface of the first magnetic body.

Hereinafter, various embodiments 400A, 400B, 800A to 30 800E and 1400 of the magnetic core 110 shown in FIG. 2 will be described below with reference to the accompanying drawings.

FIG. 3 is an exploded perspective view of an embodiment 400A of the magnetic core 110 shown in FIG. 2, FIGS. 4A to 35 4D are perspective views showing a process of forming the magnetic core 400A shown in FIG. 3, and FIGS. 5A and 5B are, respectively, a coupled perspective view and a partial cross-sectional view of the magnetic core 400A shown in FIG. 3, from which the illustration of a bobbin 430 is 40 omitted.

Referring to FIGS. 3 to 5, an embodiment 400A of the magnetic core may include a first magnetic body 410 and a second magnetic body 420.

The first magnetic body 410 and the second magnetic body 420 may differ in magnetic permeability. The second magnetic body 420 may have a higher saturation magnetic flux density than the first magnetic body 410. Here, the magnetic permeability may be expressed by the following Equation 1.

$$\mu = \mu_0 \mu_s \quad [\text{Equation 1}]$$

55 Here, μ represents magnetic permeability, μ_0 represents magnetic permeability in a vacuum (or air), which is $4\pi \times 10^{-7}$, μ_s represents relative permeability, and the unit of each of μ , μ_0 and μ_s is [Henry/meter] (hereinafter referred to as H/m).

60 Referring to Equation 1, the difference in magnetic permeability between the first magnetic body 410 and the second magnetic body 420 may mean that the first magnetic body 410 and the second magnetic body 420 have different values of relative permeability.

65 For example, the first magnetic body 410 may include ferrite, and the second magnetic body 420 may include a metal ribbon. Here, the relative permeability μ_s of the ferrite

may range from 2,000 H/m to 15,000 H/m, and the relative permeability μ_r of the metal ribbon may range from 100,000 H/m to 150,000 H/m. For example, the ferrite may be Mn—Zn-based ferrite, and the metal ribbon may be a Fe-based nanocrystalline metal ribbon. The Fe-based nanocrystalline metal ribbon may be a nanocrystalline metal ribbon including Fe and Si.

Here, the nanocrystalline material is a material with a crystallite size of 10 nm to 100 nm.

The first magnetic body 410 may be manufactured by coating ferrite powder with a ceramic or polymer binder, insulating the ferrite powder coated with the ceramic or polymer binder, and molding the insulated ferrite powder coated with the ceramic or polymer binder at a high pressure. Alternatively, the first magnetic body 410 may be manufactured by stacking a plurality of ferrite sheets on one another, each of the sheets being formed by coating ferrite powder with a ceramic or polymer binder and insulating the ferrite powder coated with the ceramic or polymer binder. However, the disclosure is not limited to any particular method of forming the first magnetic body 410.

Each of the first magnetic body 410 and the second magnetic body 420 may have a toroidal shape. The second magnetic body 420 may include at least one of an upper magnetic body 422 or a lower magnetic body 424. The second magnetic body 420 is illustrated as including both the upper magnetic body 422 and the lower magnetic body 424 in FIGS. 3 to 5. However, the disclosure is not limited thereto. In another embodiment, the second magnetic body 420 may include only one of the upper magnetic body 422 and the lower magnetic body 424.

The upper magnetic body 422 may be disposed on the top surface S1 of the first magnetic body 410, and the lower magnetic body 424 may be disposed on the bottom surface S3 of the first magnetic body 410.

The thickness of the second magnetic body 420 in the x-axis direction may be less than the thickness of the first magnetic body 410 in the x-axis direction. That is, the thickness of each of the upper magnetic body 422 and the lower magnetic body 424 in the x-axis direction may be less than the thickness of the first magnetic body 410 in the x-axis direction. The magnetic permeability of the magnetic core 400A may be adjusted by adjusting at least one of a ratio of the thickness of the upper magnetic body 422 to the thickness of the first magnetic body 410 or a ratio of the thickness of the lower magnetic body 424 to the thickness of the first magnetic body 410. To this end, each of the upper magnetic body 422 and the lower magnetic body 424 may include a metal ribbon stacked in multiple layers.

The magnetic core 400A may further include a bobbin 430. The bobbin 430 may further include an upper bobbin 432 and a lower bobbin 434.

A method of forming the magnetic core 400A shown in FIG. 3 will be described below with reference to FIGS. 4A to 4D. However, the disclosure is not limited thereto. That is, the magnetic core 400A shown in FIG. 3 may be manufactured in a manner different from that shown in FIGS. 4A to 4D.

First, referring to FIG. 4A, the upper bobbin 432, the upper magnetic body 422, the first magnetic body 410, the lower magnetic body 424 and the lower bobbin 434 are prepared.

Subsequently, referring to FIG. 4B, the lower magnetic body 424 is adhered to the bottom of the lower bobbin 434, an adhesive is applied to each of the top surface S1 of the first magnetic body 410 and the bottom surface S3 of the first magnetic body 410, the upper magnetic body 422 is adhered

to the top surface S1 of the first magnetic body 410, and the lower magnetic body 424 is adhered to the bottom surface S3 of the first magnetic body 410. Here, the adhesive may be an adhesive including at least one of epoxy-based resin, acrylic resin, silicon-based resin, or varnish. The bonding of the second magnetic body 422 and 424 to the first magnetic body 410, which is different from the second magnetic body 422 and 424, using an adhesive may prevent deterioration in performance due to physical vibration.

Subsequently, referring to FIG. 4C, the lower bobbin 434, to which the lower magnetic body 424 is adhered, and the first magnetic body 410 are assembled to each other.

Subsequently, referring to FIG. 4D, the upper bobbin 432 is assembled to the product shown in FIG. 4C.

As illustrated in FIG. 5, the embodiment 400A of the magnetic core is configured such that the upper magnetic body 422 is disposed on the top surface S1 of the first magnetic body 410 and such that the lower magnetic body 424 is disposed on the bottom surface S3 of the first magnetic body 410.

FIGS. 6A and 6B are, respectively, a coupled perspective view and a partial cross-sectional view of another embodiment 400B of the magnetic core 110 shown in FIG. 2.

Referring to FIGS. 6A and 6B, the magnetic core 400B may be configured such that the upper magnetic body 422 is disposed on one portion of the side surface S2 and S4 of the first magnetic body 410 and on the top surface S1 of the first magnetic body 410 and such that the lower magnetic body 424 is disposed on the opposite portion of the side surface S2 and S4 of the first magnetic body 410 and on the bottom surface S3 of the first magnetic body 410. The magnetic core 400B shown in FIG. 6 is the same as the magnetic core 400A shown in FIG. 5, except that the upper magnetic body 422 is disposed so as to extend from the top surface S1 of the first magnetic body 410 to the side surface S2 and S4 of the first magnetic body 410 and that the lower magnetic body 424 is disposed so as to extend from the bottom surface S3 of the first magnetic body 410 to the side surface S2 and S4 of the first magnetic body 410, and a duplicate explanation thereof will therefore be omitted.

With the above-described configuration, in which the magnetic core 400A and 400B includes the mutually different first and second magnetic bodies 410 and 420, it is possible to remove noise over a wide frequency band.

In the case in which each of the first magnetic body and the second magnetic body, included in the magnetic core 110 shown in FIG. 2, has a toroidal shape, the side surface of the first magnetic body, among the surfaces of the first magnetic body on which the second magnetic body is disposed, may be at least one of the outer circumferential surface or the inner circumferential surface of the first magnetic body. In this case, the second magnetic body included in the magnetic core 110 may be disposed on at least a portion of the top surface, the bottom surface, the inner circumferential surface or the outer circumferential surface of the first magnetic body. Still another embodiment of the magnetic core 110 will be described below with reference to the accompanying drawings.

FIGS. 7A and 7B are, respectively, a coupled perspective view and a partial cross-sectional view of still another embodiment 800A of the magnetic core 110 shown in FIG. 2, and FIGS. 8A and 8B are perspective views showing a process of forming the magnetic core 800A shown in FIGS. 7A and 7B.

Referring to FIGS. 7A to 7B, the magnetic core 800A may include a first magnetic body 810 and a second magnetic body 820.

The first magnetic body **810** and the second magnetic body **820** may differ in magnetic permeability (or relative permeability), and the second magnetic body **820** may have a higher saturation magnetic flux density than the first magnetic body **810**.

The first magnetic body **810** may include ferrite, and the second magnetic body **820** may include a metal ribbon. Here, the metal ribbon may be a thin metal strip formed of a metal material, i.e. a long and thin strip-shaped metal sheet. However, the disclosure is not limited thereto.

Here, the relative permeability μ_s of the ferrite may range from 2,000 H/m to 15,000 H/m, and exemplarily may be 10,000 H/m, and the relative permeability μ_s of the metal ribbon may range from 2,500 H/m to 150,000 H/m, exemplarily from 100,000 H/m to 150,000 H/m. For example, the ferrite may be Mn—Zn-based ferrite, and the metal ribbon may be a Fe-based nanocrystalline metal ribbon. The Fe-based nanocrystalline metal ribbon may be a nanocrystalline metal ribbon including Fe and Si.

As illustrated in FIGS. 7A AND 7B, each of the first magnetic body **810** and the second magnetic body **820** may have a toroidal shape. In this case, the second magnetic body **820** may include an outer magnetic body **822** and an inner magnetic body **824**. The outer magnetic body **822** may be disposed on the outer circumferential surface **S2** of the first magnetic body **810**, and the inner magnetic body **824** may be disposed on the inner circumferential surface **S4** of the first magnetic body **810**.

The thickness **T0** of the first magnetic body **810** in the diameter direction thereof (e.g. the y-axis direction or the z-axis direction) may be greater than the thickness of the second magnetic body **820**. That is, the thickness **T0** of the first magnetic body **810** in the y-axis direction (or the z-axis direction) may be greater than the thickness **T1O** and **T1I** of each of the outer magnetic body **822** and the inner magnetic body **824** in the y-axis direction (or the z-axis direction). The magnetic permeability of the magnetic core **800A** may be adjusted by adjusting at least one of a ratio of the thickness **T1O** of the outer magnetic body **822** to the thickness **T0** of the first magnetic body **810** or a ratio of the thickness **T1I** of the inner magnetic body **824** to the thickness **T0** of the first magnetic body **810**.

A method of forming the magnetic core **800A** shown in FIGS. 7A and 7B will be described below with reference to FIGS. 8A and 8B. However, the disclosure is not limited thereto. That is, the magnetic core **800A** shown in FIGS. 7A and 7B may be manufactured in a manner different from that shown in FIGS. 8A and 8B.

First, referring to FIG. 8A, a process of winding the outer magnetic body **822**, which is a metal ribbon, around the outer circumferential surface **S2** of the toroidal-shaped first magnetic body **810** is performed. Here, the winding process may include not only a process of winding a wire, i.e., an annular-shaped conductive wire having a diameter, around the surface of any object but also a process of winding a long and thin strip-shaped metal sheet, such as a metal ribbon, around the surface of any object.

Subsequently, referring to FIG. 8B, the inner magnetic body **824**, which is a metal ribbon that has been wound in a toroidal shape in advance, is inserted into the hollow region in the first magnetic body **810**. The inner magnetic body **824**, which has been wound in advance, may be expanded so as to fit the size of the inner circumferential surface **S4** of the first magnetic body **810**.

The outer circumferential surface **S2** of the first magnetic body **810** and the outer magnetic body **822** may be adhered to each other using an adhesive, and the inner circumferential

surface **S4** of the first magnetic body **810** and the inner magnetic body **824** may be adhered to each other using an adhesive. Here, the adhesive may be an adhesive including at least one of epoxy-based resin, acrylic resin, silicon-based resin, or varnish. The bonding of the mutually different magnetic bodies to each other using an adhesive may prevent deterioration in performance due to physical vibration.

At this time, at least one of the number of windings, the thickness **T1O** of the outer magnetic body **822** or the thickness **T1I** of the inner magnetic body **824** may be adjusted in order to obtain a desired magnetic permeability.

Each of the outer and inner magnetic bodies **822** and **824**, as illustrated in FIG. 7(a), may include a metal ribbon that is wound multiple turns and is stacked in multiple layers. The thickness **T1O** and **T1I** and magnetic permeability of each of the outer and inner magnetic bodies **822** and **824** may be varied depending on the number of layers in which the metal ribbon is stacked. The noise removal performance of an EMI filter, to which the magnetic core **800A** is applied, may be varied depending on the magnetic permeability of the magnetic core **800A**. That is, the larger the thicknesses **T1O** and **T1I** of the outer and inner magnetic bodies **822** and **824**, the higher the noise removal performance. Based on this principle, the number of layers in which the metal ribbon is stacked may be adjusted such that the thicknesses **T1O** and **T1I** of the outer and inner magnetic bodies **822** and **824**, which are disposed on a region around which the coil **120** is wound, are greater than the thicknesses **T1O** and **T1I** of the outer and inner magnetic bodies **822** and **824**, which are disposed on a region around which the coil **120** is not wound.

The number of layers of the metal ribbon may be adjusted by the number of windings, the starting point of winding and the ending point of winding. As illustrated in FIG. 8A, when the outer magnetic body **822**, which is a metal ribbon, is wound one turn from the starting point of winding around the outer circumferential surface **S2** of the first magnetic body **810**, the outer magnetic body **822** may include a one-layered metal ribbon.

Alternatively, when the outer magnetic body **822** is wound two turns from the starting point of winding, the outer magnetic body **822** may include a two-layered metal ribbon. When the starting point of winding and the ending point of winding do not coincide with each other, for example, when the outer magnetic body **822** is wound one and a half turns from the starting point of winding, the outer magnetic body **822** includes a region in which a metal ribbon is stacked in a single layer and a region in which a metal ribbon is stacked in two layers.

Alternatively, when the outer magnetic body **822** is wound two and a half turns from the starting point of winding, the outer magnetic body **822** includes a region in which a metal ribbon is stacked in two layers and a region in which a metal ribbon is stacked in three layers. In this case, if the coil **120** is disposed on a region in which the number of layers in which a metal ribbon is stacked is larger, the noise removal performance of an EMI filter to which the magnetic core **800A** according to the embodiment is applied may be further improved.

For example, in the case in which the magnetic core **800A** has a toroidal shape and in which the first coil **122** and the second coil **124** are wound opposite each other around the magnetic core **800A**, the first coil **122** may be disposed on a region in which the number of stacked layers of the outer magnetic body **822**, which is disposed on the outer circumferential surface **S2** of the first magnetic body **810**, is

relatively large, and the second coil 124 may be disposed on a region in which the number of stacked layers of the inner magnetic body 824, which is disposed on the inner circumferential surface S4 of the first magnetic body 810, is relatively large. Accordingly, each of the first coil 122 and the second coil 124 may be disposed on a region in which the number of stacked layers of a respective one of the outer and inner magnetic bodies 822 and 824 is relatively large, but may not be disposed on a region in which the number of stacked layers of a respective one of the outer and inner magnetic bodies 822 and 824 is relatively small, thereby achieving improved noise removal performance. FIG. 7A shows that the outer magnetic body 822 includes a first region and a second region. The first region includes a first number of winding layers in the outer magnetic body 822, and the second region includes a second number of winding layers in the outer magnetic body 822, and the second number of winding layers is greater than the first number of winding layers. FIG. 7A shows that the inner magnetic body 824 includes a third region and a fourth region. The third region includes a third number of winding layers in the inner magnetic body 824, and the fourth region includes a fourth number of winding layers in the inner magnetic body 824, and the fourth number of winding layers is greater than the third number of winding layers.

The outer magnetic body 822 and the inner magnetic body 824 may be formed of the same material as each other or may be formed of different materials from each other. The thicknesses T1O and T1I of the outer magnetic body 822 and the inner magnetic body 824 may be the same as each other or may be different from each other. However, the disclosure is not limited thereto. The outer magnetic body 822 and the inner magnetic body 824 may have different materials, different values of magnetic permeability, and/or different thicknesses T1O and T1I. Therefore, the magnetic permeability of the magnetic core 800A may have a wide range of values.

For example, in FIGS. 7A and 7B, the outer magnetic body 822 and the inner magnetic body 824 may be wound in the range from 5 turns to 25 turns, preferably from 10 turns to 20 turns.

Further, the thickness ratio (T1O:TO) between the outer magnetic body 822 and the first magnetic body 810 in the diameter direction (e.g. the y-axis direction or the z-axis direction) of the first magnetic body 810 may range from 1:80 to 1:16, preferably from 1:40 to 1:20. However, the disclosure is not limited thereto. In this case, the outer magnetic body 822 may be wound in the range from 5 turns to 25 turns, preferably from 10 turns to 20 turns.

Still further, the thickness ratio (T1I:TO) between the inner magnetic body 824 and the first magnetic body 810 in the diameter direction (e.g. the y-axis direction or the z-axis direction) of the first magnetic body 810 may range from 1:80 to 1:16, for example, from 1:40 to 1:20. However, the disclosure is not limited thereto. In this case, the inner magnetic body 824 may be wound in the range from 5 turns to 25 turns, preferably from 10 turns to 20 turns.

FIGS. 9A and 9B are, respectively, a coupled perspective view and a partial cross-sectional view of still another embodiment 800B of the magnetic core 110 shown in FIG. 2.

Referring to FIGS. 9A and 9B, the width (or the height h1) of the first magnetic body 810 in the x-axis direction may be greater than the width (or the height h2) of the outer and/or inner magnetic body 822 and 824 in the x-axis direction. To this end, in the process shown in FIGS. 8A and 8B, a metal

ribbon having a width h2 less than the width h1 of the first magnetic body 810 may be wound to form the second magnetic body 820.

Referring to FIGS. 9A and 9B, the outer magnetic body 822 may not be disposed on the boundary between the top surface S1 and the outer circumferential surface S2 of the first magnetic body 810 and the boundary between the bottom surface S3 and the outer circumferential surface S2 of the first magnetic body 810. The inner magnetic body 824 may not be disposed on the boundary between the top surface S1 and the inner circumferential surface S4 of the first magnetic body 810 and the boundary between the bottom surface S3 and the inner circumferential surface S4 of the first magnetic body 810. However, the disclosure is not limited thereto. The second magnetic body 820 may not be disposed on at least one of the boundary between the top surface S1 and the outer circumferential surface S2 of the first magnetic body 810, the boundary between the top surface S1 and the inner circumferential surface S4 of the first magnetic body 810, the boundary between the bottom surface S3 and the outer circumferential surface S2 of the first magnetic body 810, or the boundary between the bottom surface S3 and the inner circumferential surface S4 of the first magnetic body 810.

As illustrated in FIGS. 9A and 9B, in the case in which the second magnetic body 820 is disposed on the surface of the first magnetic body 810, the second magnetic body 822 and 824 may be prevented from cracking along at least one of the boundary between the top surface S1 and the outer circumferential surface S2 of the first magnetic body 810, the boundary between the bottom surface S3 and the outer circumferential surface S2 of the first magnetic body 810, the boundary between the top surface S1 and the inner circumferential surface S4 of the first magnetic body 810, or the boundary between the bottom surface S3 and the inner circumferential surface S4 of the first magnetic body 810.

For example, in FIGS. 9A and 9B, the outer magnetic body 822 and the inner magnetic body 824 may be wound in the range from 5 turns to 25 turns, preferably from 10 turns to 20 turns.

Further, the thickness ratio (T1O:TO) between the outer magnetic body 822 and the first magnetic body 810 in the diameter direction (e.g. the y-axis direction or the z-axis direction) of the first magnetic body 810 may range from 1:80 to 1:16, for example, from 1:40 to 1:20. However, the disclosure is not limited thereto. In this case, the outer magnetic body 822 may be wound in the range from 5 turns to 25 turns, preferably from 10 turns to 20 turns.

Still further, the thickness ratio (T1I:TO) between the inner magnetic body 824 and the first magnetic body 810 in the diameter direction (e.g. the y-axis direction or the z-axis direction) of the first magnetic body 810 may range from 1:80 to 1:16, for example, from 1:40 to 1:20. However, the disclosure is not limited thereto. In this case, the inner magnetic body 824 may be wound in the range from 5 turns to 25 turns, preferably from 10 turns to 20 turns.

FIGS. 10A and 10B are, respectively, a coupled perspective view and a partial cross-sectional view of still another embodiment 800C of the magnetic core 110 shown in FIG. 2.

In the case of the magnetic core 800A and 800B shown in FIGS. 7 to 9, the second magnetic body 820 is disposed on the outer circumferential surface S2 and the inner circumferential surface S4 of the first magnetic body 810, but is not disposed on the top surface S1 or the bottom surface S3 of the first magnetic body 810. Unlike this, according to still another embodiment, as illustrated in FIGS. 12A and 12B,

the second magnetic body **820** may be configured such that the second magnetic body **820** is disposed not only on the outer circumferential surface **S2** and the inner circumferential surface **S4** of the first magnetic body **810** but also on the top surface **S1** and the bottom surface **S3** of the first magnetic body **810**. Except for this difference, the magnetic core **800E** shown in FIGS. 12A and 12B is the same as the magnetic core **800A** shown in FIGS. 7A and 7B, and a duplicate explanation thereof will therefore be omitted.

For example, in FIGS. 10A and 10B, the outer magnetic body **822** may be wound in the range from 5 turns to 25 turns, preferably from 10 turns to 20 turns.

Further, the thickness ratio (T1O:TO) between the outer magnetic body **822** and the first magnetic body **810** in the diameter direction (e.g. the y-axis direction or the z-axis direction) of the first magnetic body **810** may range from 1:80 to 1:16, for example, from 1:40 to 1:20. However, the disclosure is not limited thereto. In this case, the outer magnetic body **822** may be wound in the range from 5 turns to 25 turns, preferably from 10 turns to 20 turns.

FIGS. 11A and 11B are, respectively, a coupled perspective view and a partial cross-sectional view of still another embodiment **800D** of the magnetic core **110** shown in FIG. 2.

In the case of the magnetic core **800A** and **800B** shown in FIGS. 7 to 9, the second magnetic body **820** includes the outer magnetic body **822** and the inner magnetic body **824**, which are respectively disposed on the outer circumferential surface **S2** and the inner circumferential surface **S4** of the first magnetic body **810**. Unlike this, according to still another embodiment, as illustrated in FIGS. 11A and 11B, the magnetic core **800D** may include the inner magnetic body **824**, but may not include the outer magnetic body **822**. The magnetic core **800D** shown in FIGS. 11A and 11B is the same as the magnetic core **800A** shown in FIGS. 7A and 7B, except that the outer magnetic body **822** is not included, and a duplicate explanation thereof will therefore be omitted.

For example, in FIGS. 11A and 11B, the inner magnetic body **824** may be wound in the range from 5 turns to 25 turns, preferably from 10 turns to 20 turns.

Further, the thickness ratio (T1I:TO) between the inner magnetic body **824** and the first magnetic body **810** in the diameter direction (e.g. the y-axis direction or the z-axis direction) of the first magnetic body **810** may range from 1:80 to 1:16, for example, from 1:40 to 1:20. However, the disclosure is not limited thereto. In this case, the inner magnetic body **824** may be wound in the range from 5 turns to 25 turns, preferably from 10 turns to 20 turns.

FIGS. 12A and 12B are, respectively, a coupled perspective view and a partial cross-sectional view of still another embodiment **800E** of the magnetic core **110** shown in FIG. 2.

In the case of the magnetic core **800A** and **800B** shown in FIGS. 7 to 9, the second magnetic body **820** is disposed on the outer circumferential surface **S2** and the inner circumferential surface **S4** of the first magnetic body **810**, but is not disposed on the top surface **S1** or the bottom surface **S3** of the first magnetic body **810**. Unlike this, according to still another embodiment, as illustrated in FIGS. 12A and 12B, the magnetic core **800E** may be configured such that the second magnetic body **820** is disposed not only on the outer circumferential surface **S2** and the inner circumferential surface **S4** of the first magnetic body **810** but also on the top surface **S1** and the bottom surface **S3** of the first magnetic body **810**. Except for this difference, the magnetic core **800E** shown in FIGS. 12A and 12B is the same as the magnetic

core **800A** shown in FIGS. 7A and 7B, and a duplicate explanation thereof will therefore be omitted.

For example, in FIGS. 12A and 12B, the second magnetic body **820**, which is disposed on the outer circumferential surface **S2** and the inner circumferential surface **S4**, may be wound in the range from 5 turns to 25 turns, preferably from 10 turns to 20 turns.

Further, the thickness ratio (T1O:TO) between the second magnetic body **820** disposed on the outer circumferential surface **S2** and the first magnetic body **810** in the diameter direction (e.g., the y-axis direction or the z-axis direction) of the first magnetic body **810** may range from 1:80 to 1:16, for example, from 1:40 to 1:20. However, the disclosure is not limited thereto. In this case, the second magnetic body **820** disposed on the outer circumferential surface **S2** may be wound in the range from 5 turns to 25 turns, preferably from 10 turns to 20 turns.

Still further, the thickness ratio (T1I:TO) between the second magnetic body **1420** disposed on the inner circumferential surface **S4** and the first magnetic body **1410** in the diameter direction (e.g., the y-axis direction or the z-axis direction) of the first magnetic body **1410** may range from 1:80 to 1:16, for example, from 1:40 to 1:20. However, the disclosure is not limited thereto. In this case, the second

magnetic body **1420** disposed on the inner circumferential surface **S4** may be wound in the range from 5 turns to 25 turns, preferably from 10 turns to 20 turns. Alternatively, the second magnetic body **1420** disposed on the inner circumferential surface **S4** may be stacked in a number within the range from 5 layers to 25 layers, preferably from 10 layers to 20 layers.

Still further, the second magnetic body may be disposed on each of the top surface **S1** and the bottom surface **S3** of the first magnetic body in the manner of being stacked in a number within the range from 5 layers to 25 layers, preferably from 10 layers to 20 layers, so as to have the same thickness as the second magnetic body disposed on the outer circumferential surface **S2** or the inner circumferential surface **S4** of the first magnetic body.

With the above-described configuration, in which the magnetic core **800A** to **800E** includes the mutually different first and second magnetic bodies **810** and **820** having different values of magnetic permeability, it is possible to remove noise over a wide frequency band.

In particular, compared to a toroidal-shaped magnetic core that is formed only of Mn—Zn-based ferrite, the magnetic core **400A**, **400B**, and **800A** to **800E** according to the embodiment is capable of effectively removing high-frequency noise by preventing concentration of the magnetic flux on the surface thereof and is capable of being applied to high-power products due to the low degree of internal saturation.

Further, the performance of the magnetic core **400A**, **400B**, and **800A** to **800E** may be adjusted by adjusting at least one of the magnetic permeability or the volume ratio of at least one of the first magnetic body **410** and **810** or the second magnetic body **420** and **820**.

FIGS. 13A and 13B are, respectively, a coupled perspective view and a partial cross-sectional view of still another embodiment **1400** of the magnetic core **110** shown in FIG. 2.

Referring to FIGS. 13A and 13B, the magnetic core **1400** may include a first magnetic body **1410** and a second magnetic body **1420**.

The first magnetic body **1410** and the second magnetic body **1420** may differ in magnetic permeability. The second

15

magnetic body **1420** may have a higher saturation magnetic flux density than the first magnetic body **1410**.

For example, the first magnetic body **1410** may include ferrite, and the second magnetic body **1420** may include a metal ribbon. Here, the relative permeability μ_s of the ferrite may range from 2,000 H/m to 15,000 H/m, and the relative permeability μ_s of the metal ribbon may range from 100,000 H/m to 150,000 H/m. For example, the ferrite may be Mn—Zn-based ferrite, and the metal ribbon may be a Fe-based nanocrystalline metal ribbon. The Fe-based nanocrystalline metal ribbon may be a nanocrystalline metal ribbon including Fe and Si.

The first magnetic body **1410** may have a toroidal shape, and the second magnetic body **1420** may be disposed on a region in the surface of the first magnetic body **1410**, around which the coil **120** is wound. For example, in the case in which the coil **120** includes a first coil **122** wound around the magnetic core **1400** and a second coil **124** wound so as to be opposite the first coil **122**, the second magnetic body **1420** may be disposed so as to cover the top surface **S1**, the outer circumferential surface **S2**, the bottom surface **S3** and the inner circumferential surface **S4** of the first magnetic body **1410** in each of the regions around which the first coil **122** and the second coil **124** are wound.

The thickness of the second magnetic body **1420** may be less than the thickness of the first magnetic body **1410** in at least one of the z-axis direction or the x-axis direction. The magnetic permeability of the magnetic core **1400** may be adjusted by adjusting a ratio of the thickness of the second magnetic body **1420** to the thickness of the first magnetic body **1410**. To this end, the second magnetic body **1420** may include a metal ribbon stacked in multiple layers.

For example, in FIGS. 13A and 13B, the second magnetic body **1420**, which is disposed on the outer circumferential surface **S2** and the inner circumferential surface **S4**, may be wound in the range from 5 turns to 25 turns, preferably from 10 turns to 20 turns. Alternatively, the second magnetic body **1420** may be disposed so as to be stacked in a number within the range from 5 layers to 25 layers, preferably from 10 layers to 20 layers.

Further, the thickness ratio (T1O:TO) between the second magnetic body **1420** disposed on the outer circumferential surface **S2** and the first magnetic body **1410** in the diameter direction (e.g., the y-axis direction or the z-axis direction) of the first magnetic body **1410** may range from 1:80 to 1:16, for example, from 1:40 to 1:20. However, the disclosure is not limited thereto. In this case, the second magnetic body **1420** disposed on the outer circumferential surface **S2** may be wound in the range from 5 turns to 25 turns, preferably from 10 turns to 20 turns. Alternatively, the second magnetic body **1420** disposed on the outer circumferential surface **S2** may be stacked in a number within the range from 5 layers to 25 layers, preferably from 10 layers to 20 layers.

Still further, the thickness ratio (T1I:TO) between the second magnetic body **1420** disposed on the inner circumferential surface **S4** and the first magnetic body **1410** in the diameter direction (e.g., the y-axis direction or the z-axis direction) of the first magnetic body **1410** may range from 1:80 to 1:16, for example, from 1:40 to 1:20. However, the disclosure is not limited thereto. In this case, the second magnetic body **1420** disposed on the inner circumferential surface **S4** may be wound in the range from 5 turns to 25 turns, preferably from 10 turns to 20 turns. Alternatively, the second magnetic body **1420** disposed on the outer circumferential surface **S2** may be stacked in a number within the range from 5 layers to 25 layers, preferably from 10 layers to 20 layers.

16

With the above-described configuration, in which the second magnetic body **420, 820** and **1420**, which is different from the first magnetic body **410, 810** and **1410**, is disposed on at least a portion of the surface of the first magnetic body **410, 810** and **1410**, it is possible to improve the noise removal performance of the magnetic core **400A, 400B, 800A** to **800E** and **1400**.

FIG. 14 is a graph showing a skin effect theory, wherein the horizontal axis represents a frequency f and the vertical axis represents a depth **5** of the skin.

FIG. 15 is a graph showing a magnetic flux depending on a depth b of the skin of a ferrite material, and FIG. 16 is a graph showing a magnetic flux depending on a depth b of the skin of a ferrite material and a metal ribbon material. In each graph, the horizontal axis represents a depth b of the skin, and the vertical axis represents magnetic flux B_m .

FIGS. 17A and 17B are graphs showing magnetic permeability μ and inductance L of a ferrite material and a metal ribbon material. In each graph, the horizontal axis represents a frequency f . The vertical axis in the graph shown in FIG. 17(a) represents magnetic permeability μ , and the vertical axis in the graph shown in FIG. 17(b) represents inductance L .

Referring to FIG. 14 and the following Equation 2, as the relative permeability μ_s of a material is higher and as the frequency f is higher, the value of the depth **5** of the skin is reduced, and the magnetic flux B_m is therefore concentrated on the surface of a material.

$$\delta \propto \frac{\rho}{\mu_s \cdot f} \quad [Equation 2]$$

Referring to FIG. 15, as the depth **5** of the skin is smaller, a higher magnetic flux B_m is applied. Because the saturation magnetic flux density of a ferrite material is 0.47 T, in the case in which the magnetic core includes only the first magnetic body **410, 810** and **1410**, which is a ferrite core, if the magnetic flux B_m is greater than 0.47 T, the magnetic core is saturated, which may deteriorate the noise removal performance.

Referring to FIG. 16, in the case in which a material, e.g. a metal ribbon material, which has a higher saturation magnetic flux density than a ferrite material, is used as the second magnetic body **420, 820** and **1420** and is disposed on the surface of the first magnetic body **410, 810** and **1410**, which is a ferrite material, the magnetic core is capable of enduring a high magnetic flux B_m at a small depth b of the skin, whereby the noise removal performance is maintained. With the configuration in which the second magnetic body **420, 820** and **1420**, which has a higher saturation magnetic flux density than the first magnetic body **410, 810** and **1410**, is disposed on at least a portion of the surface of the first magnetic body **410, 810** and **1410**, it is possible to increase the effective cross-sectional area of the magnetic core **400A, 400B, 800A** to **800E** and **1400** at a high frequency.

Referring to FIGS. 17A and 17B, the magnetic core **400A, 400B, 800A** to **800E** and **1400**, which includes the first magnetic body **410, 810** and **1410** formed of a ferrite material and the second magnetic body **420, 820** and **1420** formed of a metal ribbon material, which have different values of magnetic permeability for respective frequencies f , exhibits high inductance in a predetermined frequency range and therefore achieves high noise removal performance.

Hereinafter, the magnetic cores according to a comparative example and embodiments will be compared and described below with reference to the accompanying drawings.

FIG. 18 illustrates top views and cross-sectional views of the comparative example and Embodiments 1 to 6 of the magnetic core.

In FIG. 18, the comparative example has a configuration in which the magnetic core includes the first magnetic body 410 but does not include the second magnetic body 420, 820 and 1420. Embodiment 1, for example, as illustrated in FIG. 10, has a configuration in which the second magnetic body 822 includes only the outer magnetic body 822, which is disposed on the outer circumferential surface of the first magnetic body 810. Embodiment 2, for example, as illustrated in FIG. 11, has a configuration in which the second magnetic body 824 includes only the inner magnetic body 824, which is disposed on the inner circumferential surface of the first magnetic body 810. Embodiment 3, for example, as illustrated in FIG. 7, has a configuration in which the second magnetic body 820 includes the outer magnetic body 822 and the inner magnetic body 824, which are respectively disposed on the outer circumferential surface and the inner circumferential surface of the first magnetic body 810. Embodiment 4, for example, as illustrated in FIG. 5, has a configuration in which the second magnetic body includes the upper magnetic body 422 and the lower magnetic body 424, which are respectively disposed on the top surface and the bottom surface of the first magnetic body 410. Embodiment 5, for example, as illustrated in FIG. 12, has a configuration in which the second magnetic body 820 is disposed so as to cover the outer circumferential surface, the inner circumferential surface, the top surface and the bottom surface of the first magnetic body 810. Embodiment 6, for example, as illustrated in FIG. 13, has a configuration in which the second magnetic body 1420 is disposed on a region of the first magnetic body 1410, around which the coil 120 is wound.

FIG. 19 is a graph showing the noise removal performance of the comparative example and Embodiments 1 to 5, wherein the horizontal axis represents a thickness of a different material, which is a thickness of the second magnetic body 420, 820 and 1420, which is different from the first magnetic body 410, 810 and 1410, i.e. a thickness from the center of the magnetic core in the y-axis or z-axis direction, and the vertical axis represents additional attenuation.

FIGS. 20A and 20B show leakage inductance L_k and inductance L for each θ in Embodiment 6, respectively, FIG. 21 shows the noise reduction effect in a differential mode of the comparative example and Embodiment 3 shown in FIG. 18, and FIG. 22 shows the noise reduction effect in a common mode of the comparative example and Embodiment 3 shown in FIG. 18.

Referring to FIG. 18, in the comparative example and Embodiments 1 to 6, the first magnetic body 410, 810 and 1410 has an inner diameter ID of 16 mm, an outer diameter OD of 24 mm, and a height HI of 15 mm, and a toroidal-shaped Mn—Zn-based ferrite core is used as the first magnetic body. Further, in Embodiments 1 to 6, a Fe—Si-based metal ribbon is used as the second magnetic body 422, 820 and 1420 in such a manner that a metal ribbon having a thickness of $20 \mu\text{m} \pm 1 \mu\text{m}$ is wound or stacked. The metal ribbon may be wound in the range from 5 turns to 25 turns, preferably from 10 turns to 20 turns, or may be stacked in a number within the range from 5 layers to 25 layers, preferably from 10 layers to 20 layers.

The noise removal performance of the comparative example and Embodiments 1 to 5 was simulated under the conditions of 21 windings of a coil around the magnetic core and the application of current of 1 A (ampere) and power of 220 W. Referring to FIG. 19, it is confirmed that Embodiment 5, in which the second magnetic body 820 is disposed on the entire surface of the first magnetic body 810, achieves the highest noise removal performance and that the larger the area occupied by the second magnetic body, the higher the noise removal performance.

Comparing Embodiments 1 to 3, Embodiment 1 is configured such that the second magnetic body 822 is disposed only outside the first magnetic body 810, Embodiment 2 is configured such that the second magnetic body 824 is disposed only inside the first magnetic body 810, and Embodiment 3 is configured such that the second magnetic body 820 (822 and 824) is disposed inside and outside the first magnetic body 810. It is confirmed that the degree of attenuation of Embodiment 3 is improved by about 30% compared to that of Embodiments 1 and 2. Further, Embodiments 1 and 3 are capable of achieving improved noise removal performance with the same thickness in the diameter direction (e.g., the y-axis direction or the z-axis direction). That is, it is possible to achieve improved noise removal performance with the same size.

Still further, referring to FIG. 18, showing Embodiment 6, and FIG. 20, as the value of θ decreases, the exposed area of the first magnetic body increases, whereby the leakage inductance L_k increases and the inductance L decreases. On the other hand, as the value of θ increases, the exposed area of the first magnetic body decreases, whereby the leakage inductance L_k decreases and the inductance L increases, leading to an improvement in noise removal performance.

FIGS. 21 and 22 are views respectively showing the noise removal performance in a differential mode and the noise removal performance in a common mode, obtained by connecting the comparative example and Embodiment 3 of the magnetic core to a power board and measuring a magnetic field.

Referring to FIG. 21, compared to the comparative example, a degree of internal saturation of Embodiment 3 of the magnetic core decreases. Therefore, it is confirmed that the magnetic core according to the embodiment of the disclosure is suitable for high-power products.

Referring to FIG. 22, as the frequency becomes higher, the area efficiency of the comparative example is lowered due to the saturation of the surface of the magnetic core, whereas Embodiment 3 of the magnetic core has an improved area efficiency because the surface of the magnetic core is not saturated due to the second magnetic body 820 (822 and 824) disposed on the surface of the first magnetic body 810, and consequently has an improved noise removal effect at a high frequency.

Hereinafter, the characteristics of inductors including the comparative example and Embodiment 3 of the magnetic core, which are shown in FIG. 18, will be compared and described below with reference to the accompanying drawings. Embodiment 3 of the magnetic core shown in FIG. 18 may have the configuration of the magnetic core 800A illustrated in FIGS. 7A and 7B. However, the disclosure is not limited thereto. The inductor, which will be described below, is capable of being applied to any inductor that includes a magnetic core having an outer magnetic body and an inner magnetic body.

First, the characteristics of the inductor according to the comparative example in a differential mode will be described below.

FIG. 23 is a view showing the magnetic-field characteristics of a general inductor in a differential mode, wherein reference numerals B111 to B16 represent magnetic fields of a first coil 1122 and reference numerals B21 to B26 represent magnetic fields of a second coil 1124.

The inductor shown in FIG. 23 may include a magnetic core 1110 and first and second coils 1122 and 1124. In the case in which the inductor shown in FIG. 23 is the inductor according to the comparative example, the magnetic core 1110 includes only a first magnetic body. The first magnetic body of the magnetic core 1110, which is included in the inductor according to the comparative example, may correspond to the first magnetic body 410, 810 and 1410 shown in FIGS. 3 to 13. The first and second coils 1122 and 1124 shown in FIG. 23 are the same as the first and second coils 122 and 124 shown in FIG. 2, and a duplicate explanation thereof will therefore be omitted.

Referring to FIG. 23, most of the magnetic field that is induced in the inductor according to the comparative example by the current applied to the first and second coils 1122 and 1124 of the inductor from the outside (hereinafter referred to as "applied current") needs to be cancelled. The magnetic field B13 of the first coil 1122 and the magnetic field B23 of the second coil 1124 may have the same magnitude at an upper side of the inductor, and may therefore cancel each other out. Further, the magnetic field B14 of the first coil 1122 and the magnetic field B24 of the second coil 1124 may have the same magnitude at a lower side of the inductor, and may therefore cancel each other out. However, the magnetic field B111 of the first coil 1122 may have a larger magnitude than the magnetic field B21 of the second coil 1124 at a left side of the inductor, around which the first coil 1122 is wound, and the magnetic field B22 of the second coil 1124 may have a larger magnitude than the magnetic field B12 of the first coil 1122 at a right side of the inductor, around which the second coil 1124 is wound. As such, in the case of the inductor according to the comparative example, the magnetic fields are not actually cancelled out. Further, when high current is applied, the saturation area of the magnetic body by the magnetic fields increases, which may deteriorate performance. However, compared to the magnetic-field characteristics in a common mode to be described later, the inductor according to the comparative example may store relatively high energy due to the higher degree of cancellation of the magnetic fields.

FIG. 24 shows the configuration of the inductor shown in FIG. 23, in which the inductor is divided into three sections SE1, SE2 and SE3.

FIGS. 25A, 25B and 25C show the magnetic permeability (or relative permeability) of the first, second and third sections SE1, SE2 and SE3, respectively, at a certain time point in a differential mode of the inductor according to the comparative example. Here, the magnetic permeability may be expressed by the above Equation 1, and has a value obtained under the condition of relative permeability μ of 10,000 H/m.

In FIGS. 25A to 25C, reference numerals 910, 920 and 930 represent magnetic permeability in a mode in which low power is applied to the inductor (hereinafter referred to as a "low-power mode"), and reference numerals 912, 922 and 932 represent magnetic permeability in a mode in which high power is applied to the inductor (hereinafter referred to as a "high-power mode"). In FIGS. 25A to 25C, the horizontal axis represents a position in the radial (r) direction of the inductor. In FIGS. 23 and 24, "r=0" represents the center of the annular-shaped inductor.

Referring to FIGS. 25A to 25C, in any of the sections, the magnetic permeability of the first magnetic body of the magnetic core 1110 has a minimum value at the inner edge r1 and the outer edge r2 of the magnetic core 1110 and has a maximum value at the center rc of the magnetic core 1110. This phenomenon occurs identically both in the high-power mode 912, 922 and 932 and in the low-power mode 910, 920 and 930.

FIG. 26 is a graph showing an average magnetic permeability on the y-z plane in a differential mode of the inductor according to the comparative example, wherein the horizontal axis represents a position in the radial (r) direction of the inductor and the vertical axis represents an average magnetic permeability on the y-z plane. In FIG. 26, reference numeral 940 represents an average magnetic permeability in a low-power mode, and reference numeral 942 represents an average magnetic permeability in a high-power mode.

FIG. 27 is a graph showing an average magnetic permeability in a differential mode of the inductor according to the comparative example, wherein the horizontal axis represents current and the vertical axis represents an average magnetic permeability.

FIG. 26 shows a result obtained through line integration of the magnetic permeability, which is obtained at every time point, as illustrated in FIGS. 25A to 25C, in the circumferential direction of the inductor and structural average and time average of the line integration value when the frequency of the applied current (hereinafter referred to as an "applied frequency") is in the range from 40 Hz to 70 Hz. FIG. 27 shows a result obtained through volume integration of the result value shown in FIG. 26 and time average of the volume integration value.

Referring to FIG. 27, as the current increases in a differential mode, the average magnetic permeability of the inductor according to the comparative example decreases. When the applied current is IC1, the inductor according to the comparative example reaches a partially saturated PS state in which the inductor loses 50% of the function thereof, and as the current continuously increases, the inductor reaches a completely saturated CS state in which the inductor loses 100% of the function thereof.

Next, the characteristics of the inductor according to the comparative example in a common mode will be described below.

FIG. 28 is a view showing the magnetic-field characteristics of a general inductor in a common mode, wherein reference numerals B11 to B16 represent magnetic fields of a first coil 1122 and reference numerals B21 to B26 represent magnetic fields of a second coil 1124.

The inductor shown in FIG. 28 may include a magnetic core 1110 and first and second coils 1122 and 1124. In the inductor according to the comparative example shown in FIG. 28, the magnetic core 1110 includes only a first magnetic body. The first magnetic body of the magnetic core 1110, which is included in the inductor according to the comparative example, may correspond to the first magnetic body 410, 810 and 1410 shown in FIGS. 3 to 13. The first and second coils 1122 and 1124 shown in FIG. 28 are the same as the first and second coils 122 and 124 shown in FIG. 2, and a duplicate explanation thereof will therefore be omitted.

Referring to FIG. 28, the magnetic field B13 of the first coil 1122 and the magnetic field B23 of the second coil 1124 are added to each other at an upper side of the inductor, the magnetic field B14 of the first coil 1122 and the magnetic field B24 of the second coil 1124 are added to each other at a lower side of the inductor, the magnetic field B111 of the

first coil **1122** is added to the magnetic field **B21** of the second coil **1124** at a left side of the inductor, around which the first coil **1122** is wound, and the magnetic field **B22** of the second coil **1124** is added to the magnetic field **B12** of the first coil **1122** at a right side of the inductor, around which the second coil **1124** is wound. As such, the magnetic fields induced in the inductor by the applied current applied to the first and second coils **1122** and **1124** of the inductor according to the comparative example from the outside are not cancelled, but the magnetic fields are mostly added to each other, whereby the magnetic permeability may be easily saturated when noise is introduced (i.e. when reverse current is introduced). The function may be maintained when reflected current is equal to or less than $1/1000$ of power consumption.

The inductor shown in FIG. 28, like the inductor shown in FIG. 24, may be divided into three sections **SE1**, **SE2** and **SE3**.

FIGS. 29A, 29B and 29C show the magnetic permeability (or relative permeability) of the first, second and third sections **SE1**, **SE2** and **SE3**, respectively, at a certain time point in a common mode of the inductor according to the comparative example. Here, the magnetic permeability may be expressed by the above Equation 1, and has a value obtained under the condition of relative permeability μ_s of 10,000 H/m.

In FIGS. 29A to 29C, reference numerals **950**, **960** and **970** represent magnetic permeability in a low-power mode, and reference numerals **952**, **962** and **972** represent magnetic permeability in a high-power mode. In FIGS. 29A to 29C, the horizontal axis represents a position in the radial (r) direction of the inductor. In FIG. 28, “r=0” represents the center of the annular-shaped inductor.

Referring to FIGS. 29A to 29C, in each of the low-power mode **950**, **960** and **970** and the high-power mode **952**, **962** and **972**, the magnetic permeability of the magnetic core **1110** gradually increases from the inner edge **r1** of the magnetic core **1110** to the outer edge **r2** thereof in any of the sections.

FIG. 30 is a graph showing an average magnetic permeability on the y-z plane in a common mode of the inductor according to the comparative example, wherein the horizontal axis represents a position in the radial (r) direction of the inductor and the vertical axis represents an average magnetic permeability on the y-z plane. In FIG. 30, reference numeral **980** represents an average magnetic permeability in a low-power mode, and reference numeral **982** represents an average magnetic permeability in a high-power mode.

FIG. 31 is a graph showing an average magnetic permeability in a common mode of the inductor according to the comparative example, wherein the horizontal axis represents current and the vertical axis represents an average magnetic permeability.

FIG. 30 shows a result obtained through line integration of the magnetic permeability, which is obtained at every time point, as illustrated in FIGS. 29A to 29C, in the circumferential direction of the inductor and structural average and time average of the line integration value. FIG. 31 shows a result obtained through volume integration of the result value shown in FIG. 30 and time average of the volume integration value.

Referring to FIG. 31, as the current increases in a common mode, the average magnetic permeability of the inductor according to the comparative example decreases. When the applied current is **IC2**, the inductor according to the comparative example reaches a partially saturated PS state in which the inductor loses 50% of the function thereof, and as

the applied current continuously increases, the inductor reaches a completely saturated CS state in which the inductor loses 100% of the function thereof. Referring to FIG. 31, it is confirmed that the partial saturation is realized earlier at a lower current in the common mode **CM** than in the differential mode **DM**.

In the state in which the applied current to be used in the inductor according to the comparative example is applied in a differential manner (i.e. in the state in which the function of the magnetic body is lowered), when reverse current noise of a power factor correction circuit and reverse current noise due to switching for driving a transformer are introduced in the manner of a high-frequency (e.g. 1 kHz to 1 MHz) common mode and when high-frequency noise (e.g. 1 MHz to 30 MHz) due to other communication circuits is introduced, the noise reduction function may be lowered. The function of the inductor according to the comparative example may be greatly lowered when reverse current is introduced due to impedance mismatch between an EMI filter to be described later and the power factor correction circuit.

Next, the characteristics of Embodiment 3 of the inductor in a differential mode will be described below.

Embodiment 3 of the inductor, as shown in FIGS. 23 to 28, includes first and second coils **1122** and **1124** and a magnetic core **1110**. The magnetic core **1110**, as illustrated in FIG. 7, may include a first magnetic body **810** and a second magnetic body **820**, and the second magnetic body **820** may include an outer magnetic body **822** and an inner magnetic body **824**.

Like the inductor according to the comparative example, Embodiment 3 of the inductor, as shown in FIG. 24, may be divided into three sections.

FIGS. 32A, 32B and 32C show the magnetic permeability (or relative permeability) of the first, second and third sections **SE1**, **SE2** and **SE3**, respectively, at a certain time point in a differential mode of Embodiment 3 of the inductor. Here, the magnetic permeability may be expressed by the above Equation 1.

In FIGS. 32A to 32C, reference numerals **600**, **610** and **620** represent magnetic permeability in a low-power mode, and reference numerals **602**, **612** and **622** represent magnetic permeability in a high-power mode. In FIGS. 32A to 32C, the horizontal axis represents a position in the radial (r) direction of the inductor.

Referring to FIGS. 32A to 32C, when the applied frequency of the current applied to the first and second coils **1122** and **1124** is less than a critical frequency, in any of the sections in a low-power mode, the relative permeability (hereinafter referred to as a “first relative permeability”) of the first magnetic body **810**, which is located at the center **rc** of a magnetic sheet, is less than the relative permeability (hereinafter referred to as a “second relative permeability”) of the outer magnetic body **822**, which is located at the outer portion **r2** of the magnetic sheet, and is less than the relative permeability (hereinafter referred to as a “third relative permeability”) of the inner magnetic body **824**, which is located at the inner portion **r1** of the magnetic sheet. Alternatively, the relative permeability of the magnetic bodies, which are located at the inner portion **r1**, the outer portion **r2** and the center **rc** of the magnetic sheet, may be constant.

On the other hand, when the frequency of the current applied to the first and second coils **1122** and **1124** is equal to or greater than the critical frequency, unlike the phenomenon shown in FIGS. 32A to 32C, each of the second relative permeability and the third relative permeability becomes

less than the first relative permeability in any of the sections in a low-power mode. In Embodiment 3 of the inductor, the magnetic permeability **602**, **612** and **622** in a high-power mode may be contrary to the magnetic permeability **600**, **610** and **620** in a low-power mode.

Here, the critical frequency is a frequency at which the magnetic permeability is reversed due to a reduction in the second and third relative permeability of the second magnetic body **820** (i.e. a reduction in the induction amount due to loss of eddy current), which is embodied as a nanoribbon, at a high frequency.

The above-described critical frequency may increase as the thickness T1O and T1I of each of the outer and inner magnetic bodies **822** and **824** decreases. This is because a reduction in the induction amount due to loss of eddy current decreases as the thickness T1O and T1I of the second magnetic body **820**, which is embodied as a nanoribbon, decreases.

For example, the thickness T1O and T1I of each of the outer and inner magnetic bodies **822** and **824** is in the range from $200 \mu\text{m} \pm 10 \mu\text{m}$ ($20 \mu\text{m} \pm 1 \mu\text{m}$ and 10 turns) to $400 \mu\text{m} \pm 10 \mu\text{m}$ ($40 \mu\text{m} \pm 1 \mu\text{m}$ and 10 turns), the critical frequency may range from 150 kHz to 250 kHz. For example, when the thickness T1O and T1I of each of the outer and inner magnetic bodies **822** and **824** is $400 \mu\text{m} \pm 10 \mu\text{m}$ and when the number n of turns of each of the first and second coils **1122** and **1124** is 10, the critical frequency is 150 kHz. When the thickness T1O and T1I of each of the outer and inner magnetic bodies **822** and **824** is $200 \mu\text{m} \pm 10 \mu\text{m}$ and when the number n of turns of each of the first and second coils **1122** and **1124** is 10, the critical frequency may increase to 200 kHz to 250 kHz, for example, 200 kHz.

The inductance LDM of Embodiment 3 of the inductor in a differential mode may be expressed by the following Equation 3.

$$L_{DM} = L_{CM} - \frac{M^2}{L_{CM}} \quad [\text{Equation 3}]$$

Here, LCM represents inductance of Embodiment 3 of the inductor in a common mode and is expressed by the following Equation 4, and M represents a mutual inductance.

FIG. 33 is a graph showing an average magnetic permeability on the y-z plane in a differential mode of Embodiment 3 of the inductor, wherein the horizontal axis represents a position in the radial (r) direction of the inductor and the vertical axis represents an average magnetic permeability on the y-z plane. In FIG. 33, reference numeral **630** represents an average magnetic permeability in a low-power mode, and reference numeral **632** represents an average magnetic permeability in a high-power mode.

FIG. 34 is a graph showing an average magnetic permeability in a differential mode of Embodiment 3 of the inductor, wherein the horizontal axis represents current and the vertical axis represents an average magnetic permeability. FIG. 34 shows a result obtained through line integration of the magnetic permeability, which is obtained at every time point, as illustrated in FIGS. 32A to 32C, in the circumferential direction of the inductor and structural average and time average of the line integration value when the frequency of the current applied to the inductor is in the range from 40 Hz to 70 Hz. FIG. 34 shows a result obtained through volume integration of the result value shown in FIG. 33 and time average of the volume integration value.

Referring to FIG. 34, as the applied current increases in a differential mode, the average magnetic permeability of Embodiment 3 of the inductor decreases. When the applied current is IC3, Embodiment 3 of the inductor reaches a partially saturated PS state in which the inductor loses 50% of the function thereof, and as the current continuously increases, the inductor reaches a completely saturated CS state in which the inductor loses 100% of the function thereof. Referring to FIG. 34, in a differential mode, the current (hereinafter referred to as "partial saturation current") at which the inductor according to the comparative example DM is partially saturated is IC1, and the partial saturation current of Embodiment 3 E3D of the inductor is IC3, which is greater than IC1. As such, in a differential mode, Embodiment 3 reaches a partially saturated state at a higher current value IC3 than the comparative example. Referring to FIG. 34, in the case in which the number n of turns of each of the first and second coils **1122** and **1124** is in the range from 10 to 50, when the average magnetic permeability reaches a value corresponding to the partial saturation in a differential mode, the applied current IC3 may range from 0.4 A to 10 A.

That is, in a differential mode, a reduction in the magnetic permeability in Embodiment 3 due to an increase in the applied current (i.e. an increase in the magnitude of the magnetic field) is lower than that in the comparative example. This is because Example 3 of the inductor includes the first magnetic body **810**, which may be embodied as ferrite, and the second magnetic body **820** (**822** and **824**), which may be embodied as a nanoribbon having a higher magnetic permeability and a higher saturation magnetic flux density than the first magnetic body **810**, and because the thickness TO of the first magnetic body **810** is greater than each of the thickness T1I of the inner magnetic body **824** and the thickness T1O of the outer magnetic body **822**, based on a fact that magnetic energy is mainly concentrated on a material having a higher magnetic permeability. For example, when the number of turns of winding around each of the outer magnetic body **822** and the inner magnetic body **824** is in the range from 5 to 25, each of the thickness ratio (T1O:TO) between the outer magnetic body **822** and the first magnetic body **810** in the diameter direction of the first magnetic body **810** and the thickness ratio (T1I:TO) between the inner magnetic body **824** and the first magnetic body **810** in the diameter direction of the first magnetic body **810** may range from 1:80 to 1:16, preferably from 1:40 to 1:20. However, the disclosure is not limited thereto.

Therefore, compared to the comparative example, a reduction in the magnetic permeability in Embodiment 3 due to an increase in the current or an increase in the number of windings may be further prevented.

Next, the characteristics of Embodiment 3 of the inductor in a common mode will be described below.

FIGS. 35A, 35B and 35C show the magnetic permeability (or relative permeability) of the first, second and third sections **SE1**, **SE2** and **SE3**, respectively, at a certain time point in a common mode of Embodiment 3 of the inductor. Here, the magnetic permeability may be expressed by the above Equation 1.

In FIGS. 35A to 35C, reference numerals **700**, **710** and **720** represent magnetic permeability in a low-power mode, and reference numerals **702**, **712** and **722** represent magnetic permeability in a high-power mode. In FIGS. 35A to 35C, the horizontal axis represents a position in the radial (r) direction of the inductor.

Like the differential mode, referring to FIGS. 35A to 35C, in a low-power mode of a common mode, when the applied

frequency of the applied current applied to the first and second coils **1122** and **1124** is less than a critical frequency, in any of the sections in a low-power mode, the first relative permeability of the first magnetic body **810**, which is located at the center **r_c** of the magnetic core, is less than the second relative permeability of the outer magnetic body **822**, which is located at the outer portion **r₂** of the magnetic core, and is less than the third relative permeability of the inner magnetic body **824**, which is located at the inner portion **r₁** of the magnetic core. On the other hand, when the frequency of the current applied to the first and second coils **1122** and **1124** is equal to or greater than the critical frequency, unlike the phenomenon shown in FIGS. 35A to 35C, each of the second relative permeability and the third relative permeability becomes less than the first relative permeability in any of the sections in a low-power mode.

In Embodiment 3 of the inductor, the magnetic permeability **702**, **712** and **722** in a high-power mode gradually increases from the point **r₁** where the inner magnetic body **824** is located to the point **r₂** where the outer magnetic body **822** is located.

Like the differential mode, as the thickness **T₁₀** and **T₁₁** of each of the outer and inner magnetic bodies **822** and **824** decreases, the above-described critical frequency may increase. For example, when the thickness **T₁₀** and **T₁₁** of each of the outer and inner magnetic bodies **822** and **824** is in the range from $200 \mu\text{m} \pm 10 \mu\text{m}$ ($20 \mu\text{m} \pm 1 \mu\text{m}$ and 10 turns) to $400 \mu\text{m} \pm 10 \mu\text{m}$ ($40 \mu\text{m} \pm 1 \mu\text{m}$ and 10 turns), the critical frequency may range from 150 kHz to 250 kHz. For example, when the thickness **T₁₀** and **T₁₁** of each of the outer and inner magnetic bodies **822** and **824** is $200 \mu\text{m} \pm 10 \mu\text{m}$, the critical frequency may be 200 kHz.

The inductance **LCM** of Embodiment 3 of the inductor in a common mode may be expressed by the following Equation 4.

$$L_{CM} = \alpha \left(\mu_1 \frac{S_1}{LE_1} + \mu_{21} \frac{S_{21}}{LE_{21}} + \mu_{22} \frac{S_{22}}{LE_{22}} \right) \times \mu_0 \times n^2 \quad [\text{Equation 4}]$$

Here, α represents a coefficient, μ_1 represents the first relative permeability of the first magnetic body **810**, μ_{21} represents the second relative permeability of the outer magnetic body **822**, μ_{22} represents the third relative permeability of the inner magnetic body **824**, S_1 represents the cross-sectional area of the first magnetic body **810**, S_{21} represents the cross-sectional area of the outer magnetic body **822**, and S_{22} represents the cross-sectional area of the inner magnetic body **824**. Referring to FIG. 7B, each of S_1 , S_{21} and S_{22} may correspond to the cross-sectional area on the **z-x** plane. Referring to FIG. 18, LE_1 is a circumferential length of the first magnetic body **810** about the center thereof, LE_{21} is a circumferential length of the outer magnetic body **822** about the center thereof, LE_{22} is a circumferential length of the inner magnetic body **824** about the center thereof, and n is the number of turns of each of the first and second coils **1122** and **1124**.

Further, each of the first, second and third relative permeability μ_1 , μ_{21} and μ_{22} may vary depending on the applied frequency of the current applied to the inductor. When the number n of windings of each of the first and second coils **1122** and **1124** is 5 and when the thickness **T₁₀** and **T₁₁** of each of the outer and inner magnetic bodies **822** and **824** is $200 \mu\text{m} \pm 10 \mu\text{m}$ ($20 \mu\text{m} \pm 1 \mu\text{m}$ and 10 turns), the first relative permeability μ_1 may be 10,000 H/m, and each of the second and third relative permeability μ_{21} and μ_{22}

may range from 2500 H/m to 200,000 H/m. For example, when the above-described critical frequency is 200 kHz, the first, second and third relative permeability μ_1 , μ_{21} and μ_{22} for each applied frequency may be as follows.

When the applied frequency is 10 kHz, the first relative permeability μ_1 may be 10,000 H/m, and each of the second and third relative permeability μ_{21} and μ_{22} may range from 100,000 H/m to 200,000 H/m.

Alternatively, when the applied frequency is 100 kHz, the first relative permeability μ_1 may be 10,000 H/m, and each of the second and third relative permeability μ_{21} and μ_{22} may range from 12,000 H/m to 15,000 H/m.

Alternatively, when the applied frequency is 200 kHz, the first relative permeability μ_1 may be 10,000 H/m, and each of the second and third relative permeability μ_{21} and μ_{22} may range from 5,000 H/m to 15,000 H/m.

Alternatively, when the applied frequency is 300 kHz, the first relative permeability μ_1 may be 10,000 H/m, and each of the second and third relative permeability μ_{21} and μ_{22} may range from 2,500 H/m to 7,500 H/m.

FIG. 36 is a graph showing an average magnetic permeability on the **y-z** plane in a common mode of Embodiment 3 of the inductor, wherein the horizontal axis represents a position in the radial (**r**) direction of the inductor and the vertical axis represents an average magnetic permeability on the **y-z** plane. In FIG. 36, reference numeral **730** represents an average magnetic permeability in a low-power mode, and reference numeral **732** represents an average magnetic permeability in a high-power mode.

FIG. 37 is a graph showing an average magnetic permeability in a common mode of Embodiment 3 of the inductor, wherein the horizontal axis represents current and the vertical axis represents an average magnetic permeability.

FIG. 36 shows a result obtained through line integration of the magnetic permeability, which is obtained at every time point, as illustrated in FIGS. 35A to 35C, in the circumferential direction of the inductor and structural average and time average of the line integration value. FIG. 37 shows a result obtained through volume integration of the result value shown in FIG. 36 and time average of the volume integration value.

Referring to FIG. 37, as the applied current increases in a common mode, the average magnetic permeability of Embodiment 3 of the inductor decreases. When the applied current is **IC4**, Embodiment 3 of the inductor reaches a partially saturated **PS** state in which the inductor loses 50% of the function thereof, and as the applied current continuously increases, the inductor reaches a completely saturated **CS** state in which the inductor loses 100% of the function thereof. Referring to FIG. 37, in a common mode, the partial saturation current of the inductor according to the comparative example **CM** is **IC2**, and the partial saturation current of Embodiment 3 **E3C** of the inductor is **IC4**, which is greater than **IC2**. As such, in a common mode, Embodiment 3 reaches a partially saturated state at a higher current value **IC4** than the comparative example. That is, in a common mode, a reduction in the magnetic permeability in Embodiment 3 due to an increase in the applied current (i.e. an increase in the magnitude of the magnetic field) is lower than that in the comparative example.

Referring to FIG. 37, in the case in which the number n of turns of each of the first and second coils **1122** and **1124** is in the range from 10 to 50, the partial saturation current **IC4** may range from 0.04 A to 1 A in a common mode.

In the differential mode and the common mode, as the number n of turns increases, the partial saturation current **IC3** and **IC4** may decrease in inverse proportion to the

square n^2 of the number n of turns. For example, when the number n of turns is 10, the partial saturation current IC_3 in the differential mode may be about 10 A, and the partial saturation current IC_4 in the common mode may be about 1 A. However, if the number n of turns is increased to 50, i.e. 5 times, the partial saturation current IC_3 and IC_4 may be reduced to $\frac{1}{25}$. That is, the partial saturation current IC_3 may be reduced to 0.4 A, and the partial saturation current IC_4 may be reduced to 0.04 A.

Since Embodiment 3 of the inductor includes the second magnetic body **820**, which is different from the first magnetic body **810**, Embodiment 3 is capable of receiving high power in a differential mode. Further, since the second magnetic body **820** included in the magnetic core of Embodiment 3 of the inductor has a high saturation magnetic flux density and since the saturation magnetic flux density is maintained at a high frequency, some energy may be stored in the second magnetic body **820** even when reverse current is introduced. Therefore, even when a common mode is performed such that reverse current of 10 mA or lower is generated, it is possible to remove noise, thereby securing the stability of the circuit with respect to reverse current.

In Embodiment 3 of the inductor, the characteristics thereof in a common mode are similar to those in a differential mode. However, when reverse current (reflection) due to circuit impedance mismatch is introduced in a common mode, Embodiment 3 may convert the introduced reverse current into magnetic energy and may store the magnetic energy in the outer magnetic body **822** and the inner magnetic body **824**. Therefore, when Embodiment 3 of the inductor is applied to an EMI filter to be described later, it is possible to remove noise and to prevent reverse current from being introduced into a power source.

A circuit, in which the inductor according to the embodiment is mainly utilized, may be configured to receive differential-type home AC current having a level of 90 V to 240 V and a frequency of 40 Hz to 70 Hz as main energy and may include a rectifier diode connected to a rear end thereof in the form of a Wheatstone bridge. In this case, the main energy has a low frequency and the noise source has a low power level, whereby it is possible to obtain the above-described effects of the embodiment.

Meanwhile, the inductor according to the embodiment described above may be included in a line filter. For example, the line filter may be a line filter for noise reduction that is applied to an AC-to-DC converter.

FIG. 38 is an embodiment of an EMI filter including the inductor according to the embodiment.

Referring to FIG. 38, an EMI filter **2000** may include a plurality of X-capacitors C_x , a plurality of Y-capacitors C_y , and inductors L .

The X-capacitors C_x are respectively disposed between a first terminal P_1 of a live line **LIVE** and a third terminal P_3 of a neutral line **NEUTRAL** and between a second terminal P_2 of the live line **LIVE** and a fourth terminal P_4 of the neutral line **NEUTRAL**.

The plurality of Y-capacitors C_y may be disposed in series between the second terminal P_2 of the live line **LIVE** and the fourth terminal P_4 of the neutral line **NEUTRAL**.

The inductors L may be disposed between the first terminal P_1 and the second terminal P_2 of the live line **LIVE** and between the third terminal P_3 and the fourth terminal P_4 of the neutral line **NEUTRAL**. Here, each of the inductors L may be the inductor **100** according to the embodiment described above.

When common-mode noise is introduced, the EMI filter **2000** removes the common-mode noise due to combined impedance characteristics of primary inductance and the Y-capacitors C_y . Here, the primary inductance of the live line **LIVE** may be obtained by measuring the inductance between the first terminal P_1 and the second terminal P_2 in the state of opening the third and fourth terminals P_3 and P_4 , and the primary inductance of the neutral line **NEUTRAL** may be obtained by measuring the inductance between the third terminal P_3 and the fourth terminal P_4 in the state of opening the first and second terminals P_1 and P_2 .

When differential-mode noise is introduced, the EMI filter **2000** removes the differential-mode noise due to combined impedance characteristics of leakage inductance and the X-capacitors C_x . Here, the leakage inductance of the live line **LIVE** may be obtained by measuring the inductance between the first terminal P_1 and the second terminal P_2 in the short-circuit state of the third and fourth terminals P_3 and P_4 , and the leakage inductance of the neutral line **NEUTRAL** may be obtained by measuring the inductance between the third terminal P_3 and the fourth terminal P_4 in the short-circuit state of the first and second terminals P_1 and P_2 .

The inductor of the EMI filter **2000** according to the embodiment may be the inductor according to Embodiment 3 described above. When the thickness T_{10} and T_{11} of each of the outer and inner magnetic bodies **822** and **824** of the second magnetic body **820** is 200 μm ($20 \mu\text{m} \pm 1 \mu\text{m}$ and 10 turns), the EMI performance may be further improved as the number n of turns of each of the first and second coils **1122** and **1124** increases. For example, because saturation occurs when the number n of turns is greater than 15, the most excellent EMI characteristics may be obtained when the number n of turns is 15.

Further, in order to remove common-mode noise, the inductance LCM in a common mode, which is expressed by the above Equation 4, needs to be large, and in order to remove differential-mode noise, the inductance LDM in a differential mode, which is expressed by the above Equation 3, needs to be large. Therefore, the inductor according to the embodiment may include the first and second magnetic bodies **810** and **820**, which have S_1 , S_{21} , S_{22} , LE_1 , LE_{21} and LE_{22} determined based on the above principle. That is, since the relative permeability is not varied even when the number n of turns is varied, it is possible to maintain the inductance at a constant level by adjusting a ratio (S_1/LE_1 , S_{21}/LE_{21} and S_{22}/LE_{22}) of the cross-sectional area to the circumferential length.

The contents of the above-described embodiments may be applied to other embodiments as long as they are not incompatible with one another.

While the present disclosure has been particularly shown and described with reference to exemplary embodiments thereof, these embodiments are only proposed for illustrative purposes and do not restrict the present disclosure, and it will be apparent to those skilled in the art that various changes in form and details may be made without departing from the essential characteristics of the embodiments set forth herein. For example, respective configurations set forth in the embodiments may be modified and applied. Further, differences in such modifications and applications should be construed as falling within the scope of the present disclosure as defined by the appended claims.

Various embodiments have been described in the best mode for carrying out the disclosure.

An inductor according to embodiments may be used in various electronic circuits such as, for example, resonance

circuits, filter circuits and power circuits, and an EMI filter may be applied to various digital or analog circuits that need noise removal.

Any reference in this specification to "one embodiment," "an embodiment," "example embodiment," etc., means that a particular feature, structure, or characteristic described in connection with the embodiment is included in at least one embodiment of the invention. The appearances of such phrases in various places in the specification are not necessarily all referring to the same embodiment. Further, when a particular feature, structure, or characteristic is described in connection with any embodiment, it is submitted that it is within the purview of one skilled in the art to effect such feature, structure, or characteristic in connection with other ones of the embodiments.

Although embodiments have been described with reference to a number of illustrative embodiments thereof, it should be understood that numerous other modifications and embodiments can be devised by those skilled in the art that will fall within the spirit and scope of the principles of this disclosure. More particularly, various variations and modifications are possible in the component parts and/or arrangements of the subject combination arrangement within the scope of the disclosure, the drawings and the appended claims. In addition to variations and modifications in the component parts and/or arrangements, alternative uses will also be apparent to those skilled in the art.

What is claimed is:

1. A magnetic element, comprising:

a first magnetic member having a toroidal shape; and a second magnetic member disposed on at least one of an inner surface of the first magnetic member or an outer surface of the first magnetic member, wherein a first vertical length of the first magnetic member along an axial direction differs from a second vertical length of the second magnetic member along the axial direction, wherein the first magnetic member includes a through-hole which passes through the first magnetic member from a top surface thereof to a bottom surface thereof in a vertical direction, the toroidal shape being defined by the through-hole, and wherein the first vertical length of the first magnetic member is greater than the second vertical length of the second magnetic member.

2. The magnetic element of claim 1, wherein a first thickness of the first magnetic member along a diameter direction is greater than a second thickness of the second magnetic member along the diameter direction.

3. The magnetic element of claim 2,

wherein the second magnetic member includes a metal ribbon and a resin member that covers the metal ribbon, and wherein the metal ribbon extends along a circumferential direction so as to have a plurality of layers along the diameter direction.

4. The magnetic element of claim 3,

wherein the second magnetic member includes an inner second magnetic member disposed on the inner surface of the first magnetic member, and an outer second magnetic member disposed on the outer surface of the first magnetic member.

5. The magnetic element of claim 4,

wherein the first vertical length of the first magnetic member is greater than each of a vertical length of the inner second magnetic member and a vertical length of the outer second magnetic member.

6. The magnetic element of claim 5, wherein the first thickness of the first magnetic member along the diameter direction is greater than a thickness of each of the inner and outer second magnetic members along the diameter direction.

7. The magnetic element of claim 5, wherein the inner surface of the first magnetic member includes a top inner surface, a middle inner surface, and a bottom inner surface,

wherein the outer surface of the first magnetic member includes a top outer surface, a middle outer surface, and a bottom outer surface,

wherein the inner second magnetic member is disposed on the middle inner surface, and is not disposed on the top inner surface and the bottom inner surface, and

wherein the outer second magnetic member is disposed on the middle outer surface, and is not disposed on at least one of the top outer surface or the bottom outer surface.

8. The magnetic element of claim 2, wherein the thickness of the second magnetic member along the diameter direction is in a range of 190 μm to 210 μm .

9. The magnetic element of claim 8, wherein a thickness ratio between the second magnetic member and the first magnetic member in the diameter direction ranges from 1:80 to 1:16.

10. An EMI filter, comprising: a first magnetic member including a top surface, a bottom surface, and a through hole that is passing through the top surface and the bottom surface in a vertical direction;

a second magnetic member disposed on at least one of an inner surface of the first magnetic member or an outer surface of the first magnetic member,

wherein a vertical height along the vertical direction of the first magnetic member is greater than at least one of a vertical height along the vertical direction of an inner second magnetic member of the second magnetic member and a vertical height along the vertical direction of an outer second magnetic member of the second magnetic member.

11. The EMI filter of claim 10, wherein a thickness of the first magnetic member along a diameter direction is greater than a thickness of each of the inner and outer second magnetic members along the diameter direction.

12. The EMI filter of claim 11, wherein each of the inner and outer second magnetic members includes a metal ribbon and a resin member that covers the metal ribbon, and

wherein the metal ribbon of each of the inner and outer second magnetic members extends along a circumferential direction so as to have a plurality of layers along the diameter direction.

13. The EMI filter of claim 12, wherein the thickness of at least one of the inner or outer second magnetic member along the diameter direction is in a range of 190 μm to 210 μm .

14. The EMI filter of claim 11, wherein a portion of the inner surface of the first magnetic member does not overlap with the outer second magnetic member or the inner second magnetic member along the diameter direction.

15. The EMI filter of claim 13, wherein a thickness ratio between the inner or the outer second magnetic member and the first magnetic member in the diameter direction ranges from 1:80 to 1:16.

31

16. The EMI filter of claim 12,
wherein the first magnetic member includes a ferrite core.
17. The EMI filter of claim 16,
wherein the first magnetic member includes Fe—Si-based
material.
18. The EMI filter of claim 14,
wherein the inner surface of the first magnetic member
includes a top inner surface, a middle inner surface, and
a bottom inner surface,
wherein the outer surface of the first magnetic member
includes a top outer surface, a middle outer surface, and
a bottom outer surface,
wherein the inner second magnetic member is disposed on
the middle inner surface, and is not disposed on the top
inner surface and the bottom inner surface, and
wherein the outer second magnetic member is disposed on
the middle outer surface, and is not disposed on at least
one of the top outer surface or the bottom outer surface.

5

10

15

32

19. The magnetic element of claim 1,
wherein the second magnetic member includes an inner
second magnetic member disposed on the inner surface
of the first magnetic member, and an outer second
magnetic member disposed on the outer surface of the
first magnetic member.
20. The magnetic element of claim 1,
wherein the first magnetic member includes a top surface
and a bottom surface, and
wherein the second magnetic member is not disposed on
at least one of a boundary between the inner surface and
the top surface of the first magnetic member, a bound-
ary between the inner surface and the bottom surface of
the first magnetic member, a boundary between the
outer surface and the top surface of the first magnetic
member, or a boundary between the outer surface and
the bottom surface of the first magnetic member.
